UNITED STATES PATENT OFFICE.

CLEMENT E. HORTON, OF NEW YORK, N. Y., ASSIGNOR TO MCKINNEY MANUFACTURING COMPANY, OF PITTSBURGH, PENNSYLVANIA, A CORPORATION OF PENNSYLVANIA.

DESIGN FOR A PUSH PLATE OR SIMILAR ARTICLE.

Application filed September 28, 1928. Serial No. 28,315. Term of patent 7 years.

To all whom it may concern:

Be it known that I, CLEMENT E. HORTON, a citizen of the United States, residing at New York, in the county of New York, State of New York, have invented a new, original, and ornamental Design for a Push Plate or Similar Article, of which the following is a specification, reference being had to the accompanying drawing, forming a part thereof.

Figure 1 is a face view of a push plate or similar article showing my new design, and

Fig. 2 is an enlarged view taken on the line II-II of Fig. 1.

The dominant feature of the design and hence the claim for novelty thereof resides in the particular configuration at the tip or upper portion of the push plate.

I claim:

The ornamental design for a push plate or similar article, as shown and described.

CLEMENT E. HORTON.
